UNITED STATES PATENT OFFICE.

LUDWIG K. BIACH, OF NEW HAVEN, CONNECTICUT.

APPARATUS FOR AND METHOD OF DYEING MATERIAL.

1,415,513.

Specification of Letters Patent.

Patented May 9, 1922.

Application filed July 13, 1920. Serial No. 395,965.

To all whom it may concern:

Be it known that I, LUDWIG K. BIACH, a citizen of the United States, residing in New Haven, county of New Haven, and State of Connecticut, have invented certain new and useful Improvements in Apparatus for and Methods of Dyeing Material, of which the following is a specification.

This invention relates to improvements in apparatus for, and methods of dyeing piece goods, yarn or the like, and more especially to the dyeing of cotton goods and yarn by means of a solution of indigo white dissolved in an alkali.

According to the present practice the goods or yarn is run through a vat containing a solution of indigo white dissolved in an alkali. During the dyeing process, a foam, consisting of pure indigo blue, rises to the surface of the solution, which foam is, I believe, caused by the oxidation of the indigo white, in the solution, by the air carried into the tank by the material to be dyed. The forming of the pure indigo blue which rises to the surface of the solution as a foam is very objectionable as it weakens the dye solution within the vat and as a result the shade of the dyed material will vary unless the dyeing solution is replenished from time to time. It has been found in practice that such replenishing of the dye solution will be necessary for every 4,000 or 5,000 yards of material passing through the vat, in order that the material will be dyed a uniform shade.

The general object of my invention is to prevent the formation of the foam of indigo blue, above described, and this object is attained by subjecting substantially dry material to be dyed to a preliminary heating and superdrying treatment. The reasons why this preliminary treatment has the desired effect are not altogether clear to me, but my theory with reference to the matter is that the heating and drying of the material drives out of it much of the occluded air and moisture which are ordinarily carried into the dyeing solution by the material and cause the objectionable oxidation of the latter as above mentioned. Whatever the reason may be, however, it is a fact that this preliminary treatment of the material has the desired effect.

In the accompanying drawings, forming

part of this specification, wherein I have shown one preferred embodiment of an invention for the purpose of illustrating the principle thereof.

Figure 1 is an elevational view, somewhat diagrammatic in character, of an apparatus embodying my invention and by means of which the improved method may be carried out, and

Figure 2 is a plan view thereof.

Referring to the drawings, 1 indicates a frame of any suitable construction, which is shown as being secured by bolts to a supporting frame 2 secured to the ceiling of a room. Rotatably supported upon the frame 1 are a plurality of drying drums 3 and a plurality of water drums 4. Secured to the shafts of the several drying drums and of the water drums are gear wheels 5 which intermesh with one another whereby rotation of one of the drums will effect rotation of the other drums. Carried by the frame 1, at both sides thereof, are pipes 6 provided with branches 7 communicating with the interiors of the drying drums 3. One of the pipes 6 constitutes an inlet pipe and is adapted to be connected to a suitable source of supply of a heated fluid, such as steam, and the other of the pipes 6 serves as an exhaust pipe for the heated fluid after it has passed through the drying drums. Meshing with one of the gear wheels 5, preferably the one secured to the shaft of the lowermost drying drum, is a gear wheel 8 secured to a shaft 9 carrying a pulley 10 which is driven from a paddler of the usual type, not shown, by means of a belt 11. The paddler is driven by a belt 12 from a pulley 13 secured to a shaft 14 supported by hangers 15 secured to the ceiling. Rotation of the shaft 14 is effected by means of a suitable motor 16 which is belted to a pulley 17, secured to the shaft, by a belt 18.

Secured to the shaft 14 is a pulley 19 connected by a belt 20 with a pulley 21 rotatably supported upon standards 22. Fixed upon the shaft of the pulley 21 is a gear wheel 23 which meshes with a gear wheel 24, secured to a shaft 25, supported upon a frame 26, and having keyed thereto a brass roller 27. Positioned above the brass roller and adapted to be driven thereby is a rubber roll 28 the shaft of which is journaled in bearing blocks 29 adjustably mounted upon the

frame 26 and adapted to be raised or lowered by means of hand-screws 30 in the well known manner. The roller 27 and roll 28 constitute a squeezer for squeezing the excess dyeing solution from the material after it has passed therethrough.

Between the frame 1 and the standards 22 is a vat 31 having a rearwardly flaring portion 32, the open upper portion of which 10 extends below the squeezer frame 26 whereby the excess of the dyeing solution squeezed from the material by the roller 27 and roll 28 will be returned to the vat. Removably positioned within the vat is a suitable frame 15 33 carrying a plurality of rollers 34. The dyeing solution is introduced into the vat through a pipe 35 communicating with the vat at the lower portion thereof, and a stirrer 36, of any suitable construction, is 20 positioned within the vat and is driven by a belt or chain 37 from a pulley or sprocket 38 secured to the shaft 9. Located above the vat adjacent each end thereof, are angular guide members 39 which serve to straighten 25 and guide the material being dyed.

In operation the material to be dyed, indicated by reference numeral 40, is passed around the drying drums 3 and the water drums 4 after which it is passed around the 30 guide members 39 at the front of the vat. The material is then passed to and fro around the rollers 34 carried by the frame 33 within the vat as indicated by dotted lines. After leaving the vat the material 35 passes around the guide members 39 at the rear end thereof and between the roller 27 and roll 28 of the squeezer. As the material passes around the drying drums 3 it is heated to such an extent by the action of the 40 heated fluid therein that much of the occluded air and moisture is expelled therefrom, after which the material is cooled by being passed around the water drums 4, in order that its temperature will be lowered 45 to approximately the temperature of the vat 31. Just before entering the vat the material passes around the members 39 which serve to straighten it and guide it properly to the rollers 34 on the frame 33. As the 50 material travels through the vat, passing around the rollers 34, it is dyed by the dyeing solution within the vat in the usual manner. After leaving the vat the material passes around the members 39 adjacent the 55 rear end thereof which serve to straighten the material and to guide it properly to the rolls 27 and 28 of the squeezer between which the material passes. The squeezer serves to expel from the dyed material the 60 excess dyeing solution carried thereby which drops into the flaring portion of the vat and is used again in the dyeing process.

When material to be dyed is so treated, there will be no appreciable oxidation of the 65 indigo white of the dyeing solution and

therefore the solution will not be weakened during the dyeing process. The solution is thus maintained at its proper strength regardless of the speed at which the material is run through the vat and it is therefore 70 unnecessary to replenish the dyeing solution nearly as often, to maintain it at its proper strength as must be done when the indigo white is rapidly oxidized, as is the case when the material is dyed in accordance with the 75 present practice, although it is, of course, necessary occasionally to add to the dyeing solution within the tank a sufficient quantity of the solution to compensate for the portion thereof which is absorbed by the material 80 during the dyeing process. It will thus be seen that in accordance with my invention the shade of the dyed material will not vary during the dyeing process and it is therefore unnecessary to keep watch of the material 85 as it is being dyed in order to determine when the dyeing solution needs replenishing. Furthermore, it will be seen that there is a considerable saving in the amount of the dyeing solution necessary to effect the dyeing 90 of the material.

While I have illustrated and described my invention in connection with a preferred embodiment thereof, it will be understood that I do not intend to limit myself thereto, 95 but that I intend to cover my invention broadly in whatever form its principle may be employed.

Having thus described my invention, I 100 claim:—

1. The method of dyeing which consists in first heating and superdrying substantially dry material to be dyed, and then subjecting the material to the action of the dyeing fluid.

2. The method of dyeing which consists in first subjecting substantially dry material to be dyed to the action of dry heat, and then subjecting the material to the action of the dyeing fluid.

3. The method of dyeing which consists in subjecting the material to be dyed to the action of dry heat, lowering the temperature of the heated material, and then subjecting the material to the action of the dyeing fluid.

4. The method of dyeing which consists in first passing substantially dry material to be dyed over a dry heated surface, and then subjecting the material to the action of the dyeing fluid.

5. The method of dyeing which consists in passing the material to be dyed over a dry heated surface, then over a cold dry surface, and then subjecting the material to the action of the dyeing fluid.

6. In a dyeing apparatus, the combination of a vat adapted to contain a dyeing fluid and provided with means for guiding the material to be dyed therethrough, and means for dry heating the material and for then

100

cooling it to approximately the temperature of the dyeing fluid before the material enters the latter.

7. In a dyeing apparatus, the combination of a vat adapted to contain a dyeing fluid and provided with means for guiding the material to be dyed therethrough, a heated imperforate roller over which the material

is adapted to pass and by which it is heated and dried before it enters said vat, and another cooled imperforate roller over which the material is adapted to pass after it leaves said heated roller and before it enters said vat. 10

LUDWIG K. BIACH.
